ORNAMENTAL MATERIAL AND SHOE
MADE THEREFROM

Frank Parlante, Brooklyn, N. Y.

Application November 12, 1934, Serial No. 752,550

4 Claims. (Cl. 66—170)

The present invention relates to shoes and shoe uppers, and to ornamental materials intended primarily for shoe uppers.

One object of the invention is to provide a shoe upper material having an ornamental pattern formed therein during the process of making the material.

Another object of the invention is to pre-form at least part of the shoe upper during the process of making the material whereby it is unnecessary to cut the material into the desired shape.

A further object of the invention is to provide a shoe in which at least part of the upper is crocheted.

15 A further object of the invention is to provide at least part of the upper of a shoe with a novel ornamental material comprising intertwined or crocheted textile threads coated with a suitable lacquer.

20 The above objects of the invention and other objects ancillary thereto will best be understood from the following description considered in connection with the accompanying drawing.

In the drawing:

25 Fig. 1 is a side view of a shoe embodying the present invention;

Fig. 2 is a plan view of a shoe upper blank in flat form before it is attached to the sole, and showing a part of the counter strap in dotted lines;

30 Fig. 3 is an enlarged view of a portion of the crocheted material, showing the threads approximately twice their actual size.

Referring to the drawing in detail, the shoe, as here shown, is a lady's shoe and comprises a sole 12, 35 10 of leather or other suitable material, a heel 12, and an upper constituted by a front vamp 14, provided with a strap 16, and a heel and counter-portion 18, provided with a releasable fastener strap 20 slidably received within an opening 22 formed by a folded over portion 23 of the strap 16. While the shoe here shown is of the open-shank type, it will be understood that the invention is not restricted to a shoe of this type but may be embodied generally in shoes of other types and styles.

In describing the upper material utilized in making the shoe according to the present invention, reference will be had to the blank of upper material shown as a vamp portion 14, in Fig. 2, 50 but it will be understood that, except for the shape of the blank, other portions of the upper of the shoe or a single upper portion constituting the entire upper of the shoe, may be made in the same way. As here shown, the blank of the upper material comprises crocheted threads 24

intertwined in such a way as to produce a finished peripheral edge 26 which defines the shape of the blank, which preferably corresponds substantially to the shape of the part of the shoe for which the blank is employed. Thus, as shown in Fig. 2, 5 the blank is in the form of the vamp of an open-shank shoe and the shape of this blank is such that it may be secured to the sole of the shoe without any other shaping or cutting operations. In crocheting the vamp 14, or other part of the 10 shoe upper, the ornamental pattern may be varied to a considerable extent, and if desired spaced openings 28 may be formed, and said openings may extend transversely of the vamp in the areas indicated by the dotted lines 30. The strap 16 15 may be formed by crocheting the same integrally with the edge portion 26 of the vamp 14.

The threads 24, which are crocheted into the material of the shoe upper are textile threads coated with a suitable lacquer which will not detract substantially from their flexibility. I prefer, however, to utilize a coated thread known as Halemore coated cord which may be purchased from Maynard H. Moore Jr., Inc., of Everett, Massachusetts. This thread or other thread which 25 I prefer to utilize in crocheting the present upper material is of circular cross section and consists of a linen thread coated with a lacquer of the desired color. Also in crocheting the shoe upper according to the present invention, the crocheted 30 material may comprise portions of contrasting colors whereby to enhance the ornamental effect produced by the use of the present material. The coating on the threads is preferably lustrous.

In making the shoe, after the upper has been 35 crocheted it is stitched wrong side out to the sewing lip (not shown) of the sole, according to the well known method of making turned shoes, the stitching (not shown) passing through the edge portion 26 of the upper. Instead of securing the 40 crocheted blank to the sole directly by thus stitching the edge portion to the sole, a strip of suitable material, such as upper leather or fabric may be stitched at one edge to said sole and at the other edge to the edge 26 of the crocheted blank. Then 45 the shoe is turned, the heel attached, and the other finishing operations are performed in the usual way. The shoe may, of course, be made by any well known process other than the turn process. If desired a lining of any suitable material 50 may be applied to the crocheted material.

While I have described the preferred embodiment of my invention, it will be understood that the invention can be embodied otherwise than as specifically disclosed herein. Therefore, I do 55

not wish to be limited to the precise construction shown, except as may be required by the appended claims and the prior art.

What I claim as new and desire to secure by Letters Patent is:

1. A preformed ornamental shoe upper consisting wholly of crocheted lacquer-coated textile threads, said upper having an inner zone of ornamental open work crochet, a closely crocheted zone at the free edge thereof forming a finished edge for the upper, and a closely crocheted peripheral zone, said last zone being wide enough to provide a closely crocheted portion for firm attachment to a sole and also to provide an exposed closely crocheted trimming adjacent to the sole.
- 10 2. A preformed ornamental shoe upper comprising crocheted lacquer-coated textile threads, said upper having an inner zone of ornamental open work crochet, a closely crocheted zone at the free edge thereof forming a finished edge for the upper, and a closely crocheted peripheral zone, said last zone being wide enough to pro-
- 15 15 spaced openings and a closely crocheted peripheral zone, said last zone being wide enough to provide a closely crocheted portion for firm attachment to a sole and also to provide an exposed closely crocheted trimming adjacent to the sole.
- 20 20

vide a closely crocheted portion for firm attachment to a sole and also to provide an exposed closely crocheted trimming adjacent to the sole.

3. A preformed ornamental shoe upper comprising crocheted lacquer-coated textile threads, said upper having an inner zone of ornamental open work crochet, and a closely crocheted peripheral zone, said last zone being wide enough to provide a closely crocheted portion for firm attachment to a sole and also to provide an exposed closely crocheted trimming adjacent to the sole.

4. A preformed ornamental shoe upper comprising crocheted textile threads having a wear resisting coating, said upper having an inner zone of ornamental open work crochet having 15 spaced openings and a closely crocheted peripheral zone, said last zone being wide enough to provide a closely crocheted portion for firm attachment to a sole and also to provide an exposed closely crocheted trimming adjacent to the sole.

FRANK PARLANTE.
